Donald Lee Sickler, Baltimore, Md., assignor to National Industries, Inc., Odenton, Md., a corporation of Maryland

Original design application Nov. 6, 1967, Ser. No. 9,293.
Divided and this application Oct. 2, 1968, Ser. No. 13,824

Term of patent 14 years

Int. Cl. D6—01

U.S. Cl. D15—8

FIGURE 1 is a front perspective view of a stool, showing my design;

FIGURE 2 is a side elevational view, the seat and backrest cushion having been omitted for convenience of illustration;

FIGURE 3 is a top plan view thereof; and

FIGURE 4 is a fragmentary front elevational view of the stool of FIGURE 2.

The essential features of the stool reside in the portions shown in full lines on the drawing.

This application is a division of my earlier filed pending application Ser. No. D. 9,293 filed Nov. 6, 1967.

I claim:

The ornamental design for a stool, as shown and described.
